UNITED STATES PATENT OFFICE.

EDWARD M. SWEENEY, OF SOUTH HANOVER, MASSACHUSETTS, ASSIGNOR
OF ONE-HALF TO MORRILL A. PHILLIPS, OF SAME PLACE.

DESIGN FOR A NAIL.

SPECIFICATION forming part of Design No. 29,283, dated August 30, 1898.

Application filed July 30, 1898. Serial No. 687,362. Term of patent 14 years.

To all whom it may concern:

Be it known that I, EDWARD M. SWEENEY, a citizen of the United States, residing in South Hanover, in the county of Plymouth and State 5 of Massachusetts, have invented and produced a new and original Design for a Nail, of which the following is a specification.

Figure 1 is a front elevation of a nail, illustrating my design; and Fig. 2 is a side elevation thereof.

The leading feature of my design for a nail consists in a wedge-shaped shank connected by a neck with an overhanging head having a flat under face, the neck being reduced in thickness to form shoulders at the junction of the root of the neck with the two opposite inclined faces of the shank. The shank is shown as four-sided, two opposite sides *a a* converging to the end of the shank, its other

two sides *a' a'* being substantially parallel, 20 a neck *b* connecting the wedge-shaped shank with an overhanging head *c*, having a flat under face *c'*. The neck is reduced in thickness to form shoulders *b' b'* at the junction of the root of the neck with the two opposite 25 inclines *a a* of the shank.

Having fully described my design, what I claim is—

The design for a nail, substantially as herein shown and described.

In testimony whereof I have signed my name to this specification in the presence of two subscribing witnesses.

EDWARD M. SWEENEY.

Witnesses:

JAMES C. WATERMAN,
RODOLPH W. SWEENEY.
